UNITED STATES PATENT OFFICE.

MERRITT H. HALL, OF PHILADELPHIA, PENNSYLVANIA.

IMPROVEMENT IN MACHINES FOR CUTTING LEATHER FOR BOOT AND SHOE HEELS.

Specification forming part of Letters Patent No. **145,647**, dated December 16, 1873; application filed October 6, 1873.

To all whom it may concern:

Be it known that I, MERRITT H. HALL, of the city and county of Philadelphia and State of Pennsylvania, have invented a new and useful Machine for Cutting Leather for Shoe-Heels and other purposes, of which the following is a specification:

The nature of my invention consists in a combination of a toggle-lever with a crank-shaft, having either a continuous or reciprocating rotary motion, and cutting-block moved in the cutting operation by the toggle-lever, and in the intervals between cutting is operated by a reciprocating crank-shaft, operated by the main crank-shaft, so as to withdraw the cutting-block, and afford the operator a full view and free access to the cutter or die; and also to so move the blocks as to present another part of the surface to the action of the cutter at each successive operation of the machine.

I will now proceed to describe particularly the construction and operation of my invention, referring in so doing to the drawing annexed, and letters of reference marked thereon.

The same letters apply to the same parts in the several figures.

Figure 1 shows a front elevation, and Fig. 2 a side elevation, of the machine. Both figures are drawn to a scale of one and one-half inch per foot. Figs. 3 and 4 show modifications of parts.

A represents the frame of the machine; B and B¹, a pair of toggle-levers, hung from a shaft, B²; C, a connecting-rod, conveying motion from the crank D¹ in the shaft D to the toggle-levers. E is a circular block, susceptible of rotation on the bolt E¹, by which it is fastened to the under side of the plate E². The plate E² may be slotted to permit of adjustment of the bolt lengthwise. The front end of the plate E² is attached to the bottom of the toggle-lever B¹, and the rear end is attached to a crank, G, from which it receives a reciprocating motion. The crank-shaft G¹ receives motion from the shaft B² by means of a crank, B³, and connecting-rod G², bearing a rack, which engages in the teeth of a wheel, G³, on the shaft G¹. In vibrating back and forth, the block E is rotated by a stationary pawl, E³, fastened to the frame A. The cut-

ter or die H, placed with its edge upward on the base of the machine, and a lever, I, and plunger J, serve to discharge the cut pieces of leather from it. The crank B³ and the crank D¹ are fixed in such a relative angular adjustment to each other that the block E is over the cutter H, and practically stationary when the toggles B and B¹ are extended into a straight line, and when the toggles B and B¹ are drawn up, the block E is drawn backward out of the way of the operator.

When the machine is propelled by steam or water power, I operate the shaft D with a continuous rotary movement, employing a clutch to promptly disconnect the shaft from the driving power of the fly-wheel D⁴. When the machine is to be worked entirely by the operator, I fasten the fly-wheel tightly on the shaft, and on the rim of the wheel D⁴ fasten a weight, D⁵, in such position as to leave the toggles flexed when the weight D⁵ is at the lowest point in the wheel. I impart partially rotative motion to the shaft D by a chain, K, which is fastened by one end to a staple, K', in the shaft D, and wraps half-way around the shaft. The other end of the chain is fastened to a treadle, L, which, when depressed by the foot of the operator, causes the chain K to unwrap from the shaft D and rotates it. The momentum of the wheel D⁴ and weight D⁵ causes the shaft to make a complete revolution in the opposite direction, and wraps the chain K upon it, leaving it ready for the next impression. For the rack and pinion, a lever and connecting-rod, or a pinion and sector worked by a connecting-rod, may be substituted. These modifications are shown in Figs. 3 and 4. Their applications are obvious on inspection of the figures.

What I claim as my invention is—

1. The combination of the reciprocating block E and toggle-levers B and B¹, operated by the cranks D¹ and B³, as set forth and described.
2. The reciprocating block E, operated as described, in combination with the stationary pawl E³, as set forth.

MERRITT H. HALL.
